UNITED STATES PATENT OFFICE

GEORGE A. ROBERTSHAW, OF GREENSBURG, PENNSYLVANIA

VALVE

Application filed July 13, 1927. Serial No. 205,481.

The present invention relates broadly to the art of fluid distribution, and more particularly to a valve body of such construction that it will effectively resist the corrosive effects of the fluid being handled thereby.

It is customary at the present time in the art to which the present invention relates to construct control valves, of the character utilized for the handling of gases, of a non-ferrous material, usually brass. A good grade of brass having a high copper content has been found to corrode rapidly, probably due to a sulphide deposit which builds up thereon.

15 I have found that relatively less expensive grades of brass, ordinarily referred to as yellow brass, and having a relatively low copper content as compared to red brass, resist corrosion due to fuel gases much better than does red brass having the high copper content. It will be understood that in both red and yellow brass the actual copper content is higher than the zinc content.

Due to the general porous characteristics 25 of a casting formed from yellow brass and having the usual low copper and high zinc content, it has heretofore not been considered feasible to produce valve bodies entirely therefrom. This has necessitated the use of 30 red brass even though it is more expensive and is subject to greater corrosion.

The present invention has for one of its objects the provision of an improved valve body having not only the desired non-porous characteristics required for the utilization thereof with permeable fluids, and more particularly gas, but also of such nature that corrosion is reduced to a minimum.

40 In the accompanying drawings, there are shown more or less diagrammatically for purposes of illustration only, certain embodiments of the present invention, it being understood that the drawings do not define the 45 limits of my invention, as changes in the construction and arrangement disclosed therein may be made without departing either from the spirit of the invention or the scope of my broader claims. In the drawings:

50 Fig. 1 is a vertical sectional view through

one form of valve constructed in accordance with the present invention, and

Fig. 2 is a view similar to Fig. 1 illustrating another embodiment of the invention.

It has heretofore been proposed in the art 55 to effect a solution of the problem involved by the utilization in a non-ferrous body of a ferrous seat. The moisture content present in gases, however, has resulted in objectionable rusting of the ferrous material in such manner that continued proper seating of the valve has not been possible.

Referring more particularly to Fig. 1 of the drawings, there is illustrated a valve body 65 of suitable construction and of any desired characteristics, depending upon the particular use to which it is to be put. This body is preferably constructed of red brass having the low zinc and high copper content referred to, due to the necessity of providing a non-porous construction.

The body is formed with a countersunk seat 3 and with a second similar countersunk seat 4, preferably in concentric relation to the first seat. Cooperating with these seats 75 are tubular valve seats 5, preferably terminating at their upper edges in a common plane to provide a double seat for cooperation with a single disc valve, not shown, as well understood in the art.

The valve seats 5 are preferably constructed of yellow brass having the high zinc, low copper content, due to their greater corrosion-resisting properties.

In Fig. 2 of the drawings there is illustrated a similar construction embodying, however, a single valve seat. In Fig. 2 parts corresponding to the parts of Fig. 1 previously described in detail are designated by the same reference characters having a 85 prime affixed thereto.

In first attempting to produce a valve in accordance with the present invention, I provided a preformed yellow brass ring-shaped 90 valve seat and attempted to cast a red brass body therearound. Due to the fact, however, that yellow brass melts at a temperature of approximately 400° less than the melting point of red brass, such an operation necessarily results in a large percentage of loss 100

due to the destruction of the yellow brass valve seat during the casting operation.

It is, of course, possible in accordance with the present invention to thread the seats in the valve body and thereafter thread the valve seats into position. Such an operation, however, entails extra machine work and unless great accuracy exists there is a possibility of leakage through the threads.

10 Therefore, while the present invention contemplates the utilization of yellow brass rings secured in position by either casting or threading, it is of more particular importance commercially in connection with the following method of inserting the valve seats.

This depends upon a pressing operation, and more particularly upon the utilization of valve seat rings formed from comparatively light gauge tubes, it having been found that extreme accuracy was essential in the utilization of heavy gauge yellow brass. By utilizing light gauge tube rings and forcing them into place under pressure, it is possible 20 to provide a seat in the valve body having an internal diameter as much as ten thousandths of an inch smaller than the outside diameter of the valve seat rings, the flexibility of the rings permitting them to conform to the dimensions and contour of the seat. Not only is accurate machine work obviated, but the production of a finished valve 30 having accurately formed seats tightly secured in position frictionally by reason of the flexibility of the tube rings, is obtained in this manner.

The resulting structure also provides a raised seat without the necessity of extra machining. The provision of a seat above 40 the surrounding portion of the valve body is of distinct advantage as the countersunk channel on opposite sides thereof serves to collect dirt or other foreign particles.

The present invention also lends itself admirably to the production of knife edges on the yellow brass valve seats, as clearly indicated in the drawings, thereby obviating the necessity of providing such knife edges on the valve discs as has heretofore been customary.

Certain advantages of the present invention arise from the provision of a valve body of non-porous nature and of non-ferrous characteristics, whereby it is immune to the 50 moisture content of gases, in combination with an accurate separately formed valve seat, or seats, of non-ferrous nature and not subject to the corrosive action of gases, and especially the sulphides of manufactured 60 gases.

I claim:

1. As an article of manufacture, a brass valve body having a brass seat therein, the materials of said valve body and seat both 65 containing copper but in different propor-

tions, the proportion of copper in the valve body being greater than the proportion of copper in the valve seat.

2. As an article of manufacture, a red brass valve body having a yellow brass valve 70 seat in position therein.

3. As an article of manufacture, a valve body having a countersunk portion therein and a resilient metallic seat in engagement with said countersunk portion and of greater 75 normal diameter than the diameter of said countersunk portion, said seat comprising a section of light gauge yellow brass tube.

4. As an article of manufacture, a metallic non-ferrous valve body having a metallic non-ferrous tubular seat of resilient light gauge yellow brass tube pressed into position 80 therein and maintained in fixed relation to said body by friction irrespective of whether the valve is opened or closed.

5. As an article of manufacture, a red brass valve body having a yellow brass valve seat of light gauge tube in position therein.

In testimony whereof I have hereunto set my hand.

GEORGE A. ROBERTSHAW.
